[57] ABSTRACT

A feeding mechanism in which wire coils are supplied in succession between a pair of belts, clamped by the belts and fed stepwise by the belts until a given plurality of coils are accumulated, whereupon a number of such coils are removed together for assembly as a unit. Each coil has knots at its opposite ends and three mechanisms are arranged in sequence in the path of travel of the coils between the belts for angularly turning those coils located at one end of each of the units in stages in the pauses between stepwise advance of the belts so that such knots in the end coils face the other coils in the opposite direction.

**KNOT SETTING DEVICE IN A FEED MECHANISM
FOR HELICOIDAL WIRE SPRINGS**

BACKGROUND OF THE INVENTION

1. Field of the Invention

This invention relates to a feeding mechanism for helicoidal wire springs adapted to supply the springs for making spring members, said feeding mechanism having two endless belts between which the springs are clamped and stepwise advanced.

Specifically, the invention is directed to means in said feeding mechanism for positioning the knots formed on the end windings of such springs.

2. Prior Art

In a known feed mechanism the springs are received by a collector arm from the delivery end of a spring coiling machine and placed in succession between the belts, the arm being constructed so that each nth spring is rotated through 180° before insertion between the belts. When a sufficient number of springs are between the belts, a claw mechanism transfers a group of n springs together to a spring member finishing machine. The purpose of turning the nth spring is to bring the knots of the end coils of such spring into reversed position, while the knots of the end coils of all the other springs are in a forward facing position. In order to obtain precise alignment of the knots, it has further been proposed to associate a straightening device with at least one of the belts, said straightening device including a slide which is moved after each forward step of the belts, to contact the knot of an end coil adjacent the respective belt and produce a rotation of the spring in question. Displacement of the spring is prevented by a counterbearing member in the form of a bar. This does not, however, eliminate occasional disturbances which can arise in the collector arm especially at high operational speeds.

SUMMARY OF THE INVENTION

An object of the invention is to provide a safer and more quickly acting knot positioning device.

The invention is characterized by the provision of three consecutive mechanisms at least along one of the belts, the first mechanism comprising a straightening device whose slide can undergo two different strokes so that during a pause in the stepwise advance of the belts, the slide acts on a knot in a starting position to displace it either into the final forward position or into a second position therebeyond; the second mechanism including a dolly bar which at a given time passes behind those end coils whose knots are in the second position, and a further swivel bar which contacts such knots respectively swinging them toward said dolly bar to a third position; the third mechanism including a slide operating in conjunction with a dolly bar to turn each knot in the third position to a final reversed position.

Viewed in another way wire coils are supplied in succession between a pair of belts, clamped by the belts and fed stepwise by the belts until a given plurality of coils are accumulated, whereupon a number of such coils are removed together for assembly as a unit. Each coil has opposite end windings and the knots are formed symmetrically at end windings, the coils being fed to the belts with their knots oriented in the same direction. The invention contemplates means arranged in the path of travel of the coils between the belts for

angularly turning selected coils so that their knots face the other coils, said selected coils being those coils located at one end of each of said number of coils which are removed together to form the unit, said means including the aforesaid mechanism for turning said selected coils in stages in the pauses between stepwise advance of the belts.

BRIEF DESCRIPTION OF THE DRAWING

- 10 FIG. 1 is a diagrammatic top plan view of two endless belts for the conveyance of wire springs;
15 FIG. 2 is a diagrammatic elevational view of the ideal position of the knots of the end windings of the springs directly before their take-up into a machine for assembly of the springs;
20 FIG. 3 diagrammatically illustrates the operation of the knot setting device;
25 FIG. 4 is a plan view of a swivel mechanism of the knot setting device;
FIG. 5 is a section taken along line V—V in FIG. 4;
FIG. 6 is a top view in the direction of arrow VI in FIG. 4 with some parts omitted; and
FIGS. 7 and 8 are respective views corresponding to FIG. 4 of the swivel mechanism in different stages of operation.

DETAILED DESCRIPTION

30 FIG. 1 shows two parallel endless belts 1 passing around reversing pulleys 2 with vertical axes. A plurality of helical wire springs 3 are clamped between oppositely lying runs of the belts. At an inlet end of the endless belts 1 there is a collector arm 5 which is rotatable about a horizontal axis 4, the arm 5 carrying a gripper 6 and operating in known manner to pick up a wire spring 3 from a spring manufacturing unit (not shown) and place the spring into a starting position designated 3_1 between belts 1. Belts 1 are driven by the pulleys 2 stepwise and the operation of arm 5 is coordinated to the drive of the belts so that a spring 3 is introduced into the position 3_1 after each step of the belts. Finally, for example, ten springs 3 are located between belts 1. By means of a known gripper mechanism, the first eight springs 3 for example, are then simultaneously collected and inserted into a machine for making spring assemblies.

40 FIG. 2 shows the ideal position of the knots generally indicated at 7 of the end coils 8 of the eight front 45 springs adjacent one of the belts 1, said end coils 8 being diagrammatically indicated by circles and the knots 7 by large dots. The knots 7 are symmetrically formed at the end windings of each spring and the wires are fed to the belts with the knots oriented in the same direction.

55 It is seen in FIG. 2 that all the knots 7 are in the horizontal median plane $m-m$ of belts 1. However in the first seven end coils 8 from the left, the knot is in a front position 7_n , whereas at the eighth end coil 8_n the knot is in a reverse position 7_n . The reason for this is that, as is well known, that knots 7 should not be placed at the surface of the assembled spring member, in order to avoid damage to coverings and the like. To obtain the particular position of the end coil 8_n , the gripper 6 was hitherto mounted to swing in the longitudinal direction of arm 5 and a device was provided to ensure that on insertion of the nth spring, e.g. each eighth

spring, the gripper was turned through 180° . However, the knots 7 were not brought by collector arm 5 into the ideal position as shown in FIG. 2, for which reason a straightening device was employed to cause knots 7, which are slightly below or above the median plane $m-m$ to be accurately brought into the median plane. Although such straightening device operates excellently, faults can still arise in the known arrangement. Namely, in the operation of the device which is required from turning of the gripping device 6 through 180° , the risk of interruptions increases in proportion to increased speed of operation.

In the present knot setting or positioning device, the swivel feature of the gripper 6 is dispensed with. The knot setting device comprises as shown in FIG. 3, three swivel mechanisms 9, 10 and 11, mounted at three locations along the belts 1, at which the springs 3 stop in the course of stepwise advance of the belts.

The first swivel mechanism 9 is similar to a conventional straightening device and comprises a slide 12, which is moved after each step of the belts 1 to cause its working edge 13 to strike the knot 7 of an end coil 8 in the position 7_1 . In $n-1$ successive operating cycles, the slide 12 is displaced in the direction of the arrow to shift the knot 7_1 to the position 7_o , this being achieved by interposition of a buffer 14 in the path of travel of working edge 13 in FIG. 3. A counterbearing member in the form of a stationary horizontal dolly bar 15 engages each end coil to prevent any linear displacement of the end coil of the spring when the knot is moved to position 7_o . At each nth working period of slide 12, i.e. when the nth coil is adjacent slide 12, the buffer 14 is moved out of the path of slide 12 so that the stroke of the latter is unimpeded and knot 7_1 can then reach position 7_2 , namely displaced approximately 90° further than the other springs. The buffer 14 can cooperate with the actuator for slide 12, e.g. a piston, rather than with the slide 12 itself.

The second swivel mechanism 10 includes a dolly bar 16 and a swing bar 17, which can be moved from inactive positions 16_1 and 17_1 shown in dotted lines to their active positions shown in solid lines, in order to move knot 7_2 to position 7_3 .

The third swivel mechanism 11 is again similar to a conventional straightening mechanism and includes slide 12' having working edge 13', buffer 14' and dolly bar 15'; mechanism 11 differs from swivel mechanism 9 in that buffer 14' does not have to be removed from the path of slide 12', and functions only once during n working periods of swivel mechanism 9, specifically to bring knot 7_3 to position 7_4 , i.e. into the median plane $m-m$ in a position 180° rotated relative to 7_o . When the respective spring has then reached the front position, knot 7_4 is in position 7_n in FIG. 2.

The second swivel mechanism 10 is illustrated in greater detail in FIGS. 4-8 and it operates with greater reliability and faster than the swivel device formerly used for the gripper 6, so that substantial advantage is obtained in conjunction with the extremely reliable straightening mechanisms 9 and 11.

As appears in FIGS. 4-6, the second swivel mechanism 10 comprises a carriage 18 of angle shape with legs 19 and 20. The leg 20 has a slightly bent extension 20' at the top thereof, which is fastened to a frame 23 by screws 21 and spacers 22. Two pillow

blocks 25, omitted in FIG. 4, are secured to leg 20 by screws 24 and carry two mutually aligned guide bearings 26 for the dolly bar 16. The dolly bar 16 is of rectangular section and has a vertical surface 28 at an upper wedge-shaped pointed end 27. In the working position of the bar 16 as shown in FIGS. 4 and 5, surface 28 is in contact with the inner surface of a respective belt 1 and behind the end coil 8 of spring 3, whose knot is in position 7_2 in FIG. 3.

In order to displace the dolly bar 16, it is connected to the upper extremity of a rocking lever 31 by means of a pivot 29 which engages in a slot 30 in lever 31. Lever 31 is pivotably mounted on an overhanging portion 19' of the leg 19 by means of a nut 32 and a spacer 33 and the lower extremity 34 of lever 31 lies between two buffers 35 and 36 of a cap 38 provided on the free end of a piston rod 37. The cap 38 is guided between two parallel guides 39 fastened to the leg 19 and in the illustrated working position, the cap strikes a rubber buffer 40, which is fixed to an angle 41 secured to the carriage 18. The piston, not visible, of the rod 37 is inside a double-acting pneumatic cylinder 42, which is secured to an angle 43 fixedly attached to the carriage 18. When the rod 37 is retracted into the cylinder 42, the dolly bar 16 moves to its inactive position 16_1 shown in broken lines in FIG. 5.

A rectangular baseplate 46 is disposed in a vertical plane parallel to belt 1 and a projection 46' of the baseplate is attached to the frame 23 by screws 44 and spacers 45. The baseplate 46 has two elongated slots 47 along its centerline. Two guidepieces 48, fastened by screws 49 to a slide 50, penetrate through the slots 47. A bent extremity 51 of slide 50 is connected to a piston rod 52, whose piston is inside a double-acting pneumatic cylinder 53. The cylinder 53 is attached to an angle 54 secured on the baseplate 46, and two further rubber buffers 55 are also mounted on the angle 54 on opposite sides of rod 52. Opposite a likewise bent extremity 56 of slide 50 is a central rubber buffer 57 which is attached to an angle 58 secured to the baseplate 46.

An arm 61 is pivoted on slide 50 by a screw 59 with spacer 60, and a tension spring 62 has one end attached to the arm 61 and the other end to a bolt 63 fixed to the slide 50. The swing bar 17 is attached to arm 61.

A rectangular buffer block 64 is provided with an elongated slot, through which pass two screws 66 by means of which the block 64 can be adjustably attached on baseplate 46. In order to support the block 64 when the screws 66 are loosened and the position of the block is being adjusted, two guide pins are attached to baseplate 46 beneath block 64.

FIG. 7 shows one position of swivel mechanism 10, wherein slide 50 is in its extreme rightward position with its bent extremity 56 adjacent buffer 57 and the swing bar 17 in its inactive position shown at 17_1 in FIG. 3, while the dolly bar 16 has already been displaced to its operating position by corresponding control of the compressed air supplied to cylinder 42. In the inactive position, the swing bar 17 is approximately aligned with slide 50, while arm 61 adjoins the front surface 68 (FIG. 7) of buffer block 64 under the action of spring 62. If the slide 50 is now pulled leftward by cylinder 53, arm 61 will slide on the edge 69 of block 64, and it will swing together with bar 17 in the

direction of arrow 70. FIGS. 4-6 correspond to the instant when, because of this swinging movement the bar 17 meets the knot of end coil 8 lying in position 7_2 and thereupon the knot begins to swing backward, while the dolly bar 16 prevents displacement of the end coil 8. As slide 50 moves further to the left, the arm 61 comes to rest against the side face 71 of block 64 and the task of the swing bar 17 is finished, having carried the knot to position 7_3 .

It can be seen from FIG. 8 that the hypothetical centerline of spring 62 in this extreme working position of the swing bar 17 is also somewhat below the hypothetical axis of rotation of arm 61, so that on the next righward movement of slide 50, the spring 62 exerts a force on arm 61 to exert a torque thereon in a direction opposite to that of arrow 70 and thus will return bar 17 to its inactive position as in FIG. 7.

Before the belts 1 are again moved forward one step, the cylinder 42 is activated to cause rod 37 to move upward in FIG. 5 and in so doing swing the lever 31 in the direction of arrow 72 and move the dolly bar to its inactive position 16₁, in which it will not impede the forward motion of the next spring 3 on the succeeding forward step. Position 16₁ is determined by contact of lever 31 with a rubber buffer 73 attached to the lower pillow block 25.

FIG. 5 shows the inside surfaces of both belts 1 which clamp the spring 3. The present knot setting device has only a single swivel mechanism 10, since it is sufficient to swing only one knot backward from position 7_2 into position 7_3 in order for the entire spring to join in this movement. Thus, the knot at the opposite end of coil 8 will simultaneously arrive at a position which though not necessarily corresponding exactly to position 7_3 is at least approximately thereto.

However, two opposing swivel mechanisms 9 and two facing swivel mechanisms 11 are preferably employed since it is desirable that the knot positions 7_0 and 7_4 be exactly attained at both ends coils 8 of the respective springs 3. Provision of two swivel mechanisms 10 is of course feasible, but the expenditure may be unnecessary.

It should further be mentioned that the ideal position of knots 7 shown in FIG. 2 is not absolute, as it is merely required that the knot positions 7_0 and 7_n be obtained with the first and the last spring. In the intervening springs, the knots can lie in position 7_n as well as in position 7_0 . It is simplest however for the second and third swivel mechanisms 10 and 11 to operate on only one of n springs instead of with several or even $n - 1$ springs. The first swivel mechanism 9 must of course operate with each spring namely either until the respective knot from position 7_1 has arrived at position 7_0 or until it has reached position 7_2 . Depending on the position of the end coil knots at the outlet of the spring coiling machine, it is possible for the mechanism 9 to be mounted beneath the belts 1 and the mechanisms 10 and 11 above the belts 1.

What is claimed is:

1. In a feeding mechanism in which wire coils are supplied in succession between a pair of belts, clamped by the belts and fed stepwise by the belts until a given plurality of coils are accumulated, whereupon a number of such coils are removed together for assembly as a unit, each coil having opposite ends

windings with knots formed symmetrically at said end windings, the coils being fed to the belts with their knots oriented in the same direction, an improvement comprising means arranged in the path of travel of the coils between the belts for angularly turning selected coils so that their knots face in opposite direction said selected coils being those coils located at one end of said number of coils which are removed together to form the unit, said means including mechanisms for turning said selected coils in stages in the pauses between stepwise advance of the belts.

2. An improvement as claimed in claim 1 wherein the coils are fed to the belts with their knots facing in the same direction, said means turning said selected coils about 180° so that their knots face the knots of the other coils.

3. An improvement as claimed in claim 1 wherein said mechanisms are three in number and arranged in sequence in the direction of travel of the coils adjacent at least one said belt.

4. An improvement as claimed in claim 3 wherein the coils are aligned between the belts one after another with their axes in a common plane, the coils being transported by the belts along said plane, the first of said mechanisms including a transversely movable slide for displacing the knots of the selected coils to a position offset from said plane, the second of said mechanisms including a swivel bar having a retracted position out of the path of travel of said coils and an operative position in which the bar is pivotably raised to contact the offset knot of a selected coil and angularly displace said knot towards its final position, the third of said mechanisms including a transversely movable slide for displacing the knots of the selected coils to their final angularly displaced positions.

5. An improvement as claimed in claim 4 wherein each said mechanism includes a counter bearing member acting on the coil in the course of displacement of said knots to prevent linear displacement of said coils.

6. An improvement as claimed in claim 5 wherein said slides of the first and third mechanisms travel in respective opposite directions.

7. An improvement as claimed in claim 6 wherein said slide of said first mechanism has two strokes and said first mechanism acts on all coils, said slide undergoing a first longer stroke to displace the knots of said selected coils beyond said plane, and undergoing a shorter second stroke to bring initially offset knobs of the other coils into said plane.

8. An improvement as claimed in claim 7 wherein said second mechanism comprises a pivotal lever connected to said counter bearing member, means slidably supporting said counter bearing member and double-acting cylinder means coupled to said lever to move the counter bearing member between operative and inoperative positions.

9. An improvement as claimed in claim 8 wherein said counter bearing member is slidably dolly bar having an extremity adjoining a respective belt when said dolly bar is in operative position.

10. An improvement as claimed in claim 7 wherein said second mechanism comprises a slide member carrying said swivel bar, means for displacing said slide member in opposite directions, and an adjustable and

fixable block adjacent said slide member for displacing the swivel bar to operative position as the slide member is displaced in one direction.

11. An improvement as claimed in claim 10 wherein said second mechanism further comprises spring means acting on said swivel bar to oppose movement thereof to said operative position and to apply force to said swivel bar to displace the same to inoperative position when the slide member is displaced in the opposite

direction.

12. An improvement as claimed in claim 10 wherein said swivel bar includes a depending arm which is urged by the spring means against a front face of said block in the inoperative position, said arm pivoting about an edge of said block when raised to operative position and sliding along a side face of said block as the sliding member is displaced.
